UNITED STATES PATENT OFFICE.

ROBERT BRUCE STEWARD, OF MAPLEWOOD, NEW JERSEY, ASSIGNOR TO STEWARD
DAVIT & EQUIPMENT CORPORATION, OF NEW YORK, N. Y., A CORPORATION OF
NEW YORK.

SHIP'S DAVIT.

1,332,366.

Specification of Letters Patent.

Patented Mar. 2, 1920.

Application filed March 14, 1919. Serial No. 282,600.

To all whom it may concern:

Be it known that I, ROBERT BRUCE STEWARD, a citizen of the United States, and a resident of Maplewood, county of Essex, 5 and State of New Jersey, have invented certain new and useful Improvements in Ships' Davits, of which the following is a specification.

My invention relates to ships' davits, and 10 particularly to that type of davit employing a boom or crane movable in a vertical plane to carry a life-boat and its load outboard and inboard of a ship. A type of ship's davits to which my invention is applicable 15 is shown in U. S. Patents Nos. 1,123,132 and 1,245,752, granted to T. H. Marten, December 24, 1914 and November 6, 1917, respectively.

One object of my invention is to relieve 20 the means employed to move the boom or crane and its attached load, from the strains and stresses imposed by the load and to transmit them to the frame. A further object of my invention is to so improve the 25 davit as to stabilize it against all strains and stresses to which the davit is subjected, under all conditions of weather, when the boom is moved to launch or deck the life-boat, or is dragging the life-boat through 30 water.

I will describe a ship's davit embodying my invention and then point out the novel features thereof in claims.

In the accompanying drawings Figure 1 35 is a side elevation of a ship's davit embodying my invention. Fig. 2 is a detail view showing in vertical cross-section, a part of the davit frame, the boom, a carriage to which it is pivotally connected and a manner of supporting the carriage on the davit 40 frame, and embodying my invention. Fig. 3 is a detail view, also in vertical cross-section of the carriage of Fig. 2 and a portion of the operating screw. Fig. 4 is a view of 45 a boom, partly in vertical section shown in Figs. 1 and 2, and embodying my invention. Fig. 5 is a side elevation thereof. Fig. 6 is a cross-sectional view thereof on the line 6—6, Fig. 5, but drawn to a larger scale. Fig. 7 is a detail view of a link and the 50 connection for connecting the lower end of the boom with the frame. Fig. 8 is a detail view of one of the bearings for one end of the operating screw.

55 Referring to the drawings: 1 designates a

suitable frame or support; 2 a boom or crane; 3 a truck or carriage which is movable on the frame and on which the boom 2 is pivotally mounted; and 4 an operating member, here shown as a screw, for moving 60 the truck 3 to and fro on the frame. The ends of the screw 4 are journaled in suitable bearings carried in brackets 10 and 11 secured to the frame. The journal in bracket 11 is shown in detail in Fig. 8 and as here 65 shown comprises a bearing 11^a of Babbitt or other anti-friction metal and two nuts 11^b and 11^c to take up the end thrusts due to the reverse turning movements of the screw 4. The lower end of the boom 2 is connected by a link 5 with the frame 1. The brackets 10 and 11 are connected by a rod or bar 12. The parts so far described are 70 all well-known and operate in the manner and for the purposes set forth in the patents 75 hereinbefore mentioned. However, in my invention the rod or bar 12 is made to perform a function not incident to the structures disclosed in these patents.

The truck 3 carries rollers 3^a suitably 80 journaled therein, and which travel on the upper member 1^a of the frame. The truck also carries a pivot pin 3^b the ends of which extend through the bifurcations 2^a, 2^b of the boom and act as a pivot therefor. 85 The truck also carries a nut 3^c through which the screw 4 passes. The nut 3^c is held between two lugs or projections 3^d formed on or carried by the carriage 3. Reverse turning movements are given the 90 screw 4 by the crank 4^a to cause the truck 3 to move to and fro on the frame.

In order to relieve the screw 4 of all the strains and stresses which might be imparted to it through the boom 2 when carrying a load, and to deliver or transmit such strains and stresses to the frame 1, I provide bearing surfaces on the truck 3 which are preferably located above and below the screw 4, and which bearing surfaces engage 95 the frame 1. One set of bearing surfaces are formed by flanges 3^e which embrace the bar 12 comprised in the frame 1, while the lower set of bearing surfaces are formed by flanges 3^f which embrace the member 1^a of 100 the frame. Babbitt-metal or other anti-friction surfaces 3^g are preferably provided between the sets of flanges 3^e and 3^f and the frame 1.

The boom 2 has bifurcations 2^a and 2^b as 110

shown, and the leg 2^b has a greater cross-section at the portion 2^c than the leg 2^a at its corresponding portion. The greater amount of metal therefore is in that leg of the boom which is opposite the eye 2^d. In practice it has been found that the line on which the forces fell, due to the load supported from the eye of the boom, is a straight line from the eye of the boom diagonally through the boom to the foot of the leg opposite the eye. Therefore by this arrangement of metal a stiffer boom is obtained to take care of all pulling and lateral strains. The link 5 is also wider so as to afford a greater bearing at the foot of the boom where it is connected with the boom and with the frame by the pins 5^a and 5^b. As will be seen from Fig. 7, the link 5 is connected with the pins 5^a, 5^b at their ends, the link being recessed or cut out at its ends to afford the necessary clearances for the bearing on the frame for the pin 5^a and the bifurcations 2^a, 2^b of the boom 2.

Having thus described my invention, what I claim as new is:

1. The combination in a ship's davit, of a frame, a boom pivoted thereon, operating means for moving the boom on its pivot, and means located on opposite sides of the operating means for relieving it from the strains and stresses of a load carried by the boom and transmitting them to said frame.
2. The combination in a ship's davit, of a frame, a boom, a carriage movable on said

frame and carrying a pivot for said boom, 35 operating means for moving said carriage to and fro on said frame, and means on the carriage engaging the frame on opposite sides of the operating means for relieving it from and transmitting to the frame the 40 strains and stresses due to a load carried by the boom.

3. The combination in a ship's davit, of a frame, a boom, a carriage movable on said frame and carrying a pivot for said boom, 45 means for moving the carriage to and fro on said frame, and means located on opposite sides of the means for moving the carriage, carried by said carriage and co-acting with and having a sliding bearing on 50 said frame.

4. The combination in a ship's davit, of a frame, a boom, a carriage mounted to move to and fro on said frame and having a pivoted connection with the boom, means for 55 moving the carriage to and fro on the frame, and flanges on the carriage located above and below the said operating means for relieving said operating means and transmitting to the frame the strains and stresses 60 due to a load carried by the boom.

In witness whereof I have signed my name to this specification, in the presence of two subscribed witnesses.

ROBERT BRUCE STEWARD.
